Ray O. Neyman, Kansas City, Mo., assignor to Consolidated Thermoplastics Company, Stamford, Conn., a corporation of Delaware

Filed May 7, 1963, Ser. No. 74,782

Term of patent 14 years

(Cl. D58—6)

FIG. 1

FIG. 2

FIG. 3

FIG. 4

The side and end not shown in FIGURES 1 and 2 are substantially the same as the side and end shown.

The dominant features of my design are shown in solid lines in the figures.

The characteristic features of my design reside in a bottle of the configuration shown in combination with the ornamental band placed at the constricted upper one third portion of the bottle and exhibiting a smooth transition with the bottle side walls as shown.

I claim:

The ornamental design for a bottle, as shown and described.
